(57) **CLAIM**

The ornamental design for a gaming object flipper, as shown and described.

DESCRIPTION

FIG. 1 is a front left side perspective view of a gaming object flipper in accordance with the present design.

FIG. 2 is a front view for the gaming object flipper in accordance with the embodiment of the present design.

FIG. 3 is a rear view for the gaming object flipper in accordance with the embodiment of the present design.

FIG. 4 is a right side view of the gaming object flipper in accordance with the embodiment of the present design.

FIG. 5 is a left side view for the gaming object flipper in accordance with the embodiment of the present design.

FIG. 6 is a top view for the gaming object flipper in accordance with the embodiment of the present design; and, FIG. 7 is a bottom view for the gaming object flipper in accordance with the embodiment of the present design.

The gaming object flipper can be mounted on a gaming console. The gaming console shown in broken lines depict environmental structure and form no part of the claimed design. The remaining broken lines in FIGS. 1-7 depict portions of the gaming object flipper that form no part of the claimed design.
